UNITED STATES PATENT OFFICE.

D MCRA LIVINGSTON, OF NEW YORK, N. Y.

DESIGN FOR A RADIATOR-MASK.

48,323.

Specification for Design.

Patented Dec. 21, 1915.

Application filed June 19, 1915. Serial No. 35,181. Term of patent 14 years.

To all whom it may concern:

Be it known that I, D MCRA LIVINGSTON, a citizen of the United States, and a resident of the city of New York, borough of Manhattan, in the county and State of New York, United States of America, have invented a new, original, and ornamental Design for a Radiator-Mask, of which the following is a specification, reference being had to the accompanying drawing, forming part thereof.

Figure 1 is a front perspective view of a radiator mask embodying my new design; and Fig. 2 is a perspective view taken at the side.

My improved design presents an angularly projecting grid and a frame therefor presenting dominating rearwardly curved surfaces. The improved design is thus characterized by curved lines of the frame merging into and joining the straight vertical front lines and straight vertical side lines with the straight lines of the top surface, giving effects of dominating rounding lines

in the general ensemble. The profile presents a vertical median front line extending to within a short distance of the straight top surface lines, the forward end of the top rounding upwardly and rearwardly from the vertical front line to the top surface, said top surface presenting a straight line as viewed in profile. Similarly, as viewed in front, the top of the frame presents rounding exterior lines curving in general dome form transversely, giving an arch effect, while the rearwardly diverging side lines of the top merge on rounding lines with the top surface, and, at the rear on rounding lines with the vertical sides of the frame.

I claim—

The ornamental design for a radiator mask, as shown and described.

D MCRA LIVINGSTON.
